CLAIM

We claim the ornamental design for a docking station for an ultrasound device, as shown and described.

DESCRIPTION

FIG. 1 is a top left front perspective view of a docking station for an ultrasound device showing our new design;
FIG. 2 is a bottom right perspective view thereof;
FIG. 3 is a top view thereof;
FIG. 4 is a bottom view thereof;
FIG. 5 is a right side view thereof;
FIG. 6 is a left side view thereof;
FIG. 7 is a front view thereof; and,
FIG. 8 is a rear view thereof.

The dashed broken lines illustrate portions of the docking station and form no part of the claimed design.
